UNITED STATES PATENT OFFICE.

WILLARD R. EBERLY, OF ST. PAUL, MINNESOTA.

CARBURETOR ATTACHMENT.

Application filed March 27, 1926. Serial No. 97,992.

My invention relates to a carburetor attachment for internal combustion engines and the object is to provide a simple, efficient and inexpensive means readily attached to a carburetor and operating in conjunction with the latter to provide automatically the best possible mixture of air and fuel for the combustion chamber of the engine.

In the accompanying drawing:

Fig. 1 is a longitudinal sectional elevation of my device attached to a carburetor of an engine.

Fig. 2 is a top view of my device, a portion of the carburetor, and omitting the air chamber 12 of Fig. 1.

Fig. 3 is an end view of my device showing the flange for connecting it to a carburetor.

Referring to the drawing by reference numbers, 5 designates a carburetor of an internal combustion engine, 6 is the intake manifold conducting the fuel mixture to the engine. Fuel such as gasoline, kerosene or distillate is admitted in any suitable manner 25 (not shown) into the bowl of the carburetor and maintained at a certain level by any suitable device. 5^a is the usual air passage in the upper part of the carburetor and through which air is drawn through manifold 6 to the compression chambers of the engine by the suction of the intake strokes of the pistons. 7 is a pipe, of any suitable material, for conducting heated or filtered air to the carburetor and usually connected 35 directly with it. My device comprises a stationary pipe 8 flanged as 8^a (Fig. 3) to be secured to the flanged air intake end 5^b of the carburetor, thus aligning the tubes 8 and 5^a. The interior of tube 8 comprises 40 preferably two spiral passage ways formed by a twisted diametral web 8^w and extending radially from a central core 10. This spiral may extend the full length of the tube but preferably ends in spaced relation to the free end of the tube. In said latter end the tube is provided with a number of intake holes 11. 12 is a housing inclosing the latter end of the tube 8 and has an intake 11^a to which is connected the tube 7. 13 is a cap 45 slidable on and normally closing the end of tube 8. The open end of the cap may be flanged as at 13^a for engagement by one end of an expanding coil spring 14 about tube 8 and the other end of said spring engaged 50 by the inner end of a threaded and flanged nut 15 slidable on tube 8 and its threads

engaging in a threaded aperture 12^a of the housing 12, said aperture being in the side of the housing nearest the carburetor. Adjustment of compression on spring 14 is accomplished by turning the exposed flange of nut 15, movement of cap 13 being limited by pins 16 fixed in tube 8 and extending radially therefrom through slots 13^s in the cap. 17 are intake apertures in cap 13 each located so that when the cap is in its rear position will partly overlap the apertures 11 in tube 8 and admit a small amount of air as at 18 in Fig. 2. When the engine is running the partial vacuum or so-called suction through pipe 8, pipe 5^a and manifold 6 will cause cap 13 to slide toward the carburetor and the apertures 11—13^s will come more and more into alignment and thus enlarge the air intake openings 18 and admitting air in quantities as needed according to the speed of the engine. The air will of course be drawn directly into the spiral passages of tube 8 and when reaching the carburetor will have a strong rotary or spinning motion and mix very thoroughly with the gas vapor in the mixing chamber of the carburetor and also during the continued movement of the mixture up through the manifold to the engine.

It will be readily understood that the whirling currents of air in the carburetor causes a thorough mixing of the fuel vapor and air, breaking up the fuel particles and creating a practically perfect gas mixture 90 that is drawn into the combustion chambers of an engine. The device has proven economical where gasoline is used as fuel but is particularly useful on engines using kerosene for fuel and where the air is preheated 95 by any of various well known means in use on tractors or other heavy duty engines.

What I claim is:

An air intake regulating device for a carburetor with an air intake, said device comprising a tubular member having spiral passages, one end of said tube detachably securable to said carburetor intake, said tube having air inlet ports adjacent its free end, means on said latter end for automatically 100 regulating the intake of air and an air chamber about said intake end of the tubular element, said air intake regulating means comprising a cap slidable on the free end portion of the tube and having a closed end adjacent the end of the tube, said cap having 105 ports located to register longitudinally with

the ports in the tube, a screw threaded nut 5
slidable on the tube and engaging threads
in said air chamber, a compression coil
spring about said tube, within said chamber,
and normally under compression between
said nut and the adjacent end of the cap,
said air ports in the cap and tube arranged

to provide graduated air intake to the tube
according to the position of the cap, and
means limiting the movement of said cap in 10
a direction toward the free end of the tube.

In testimony whereof I affix my signature.

WILLARD R. EBERLY.
